CHUCK WAGON CAMPER

Joshua D. Hall, New York, N.Y.
(Boiling Spring Lakes, N.C. 28461)

Filed Dec. 16, 1971, Ser. No. 211,173

Term of patent 14 years

Int. Cl. D12—10

U.S. Cl. D14—3 F

FIG. 1

FIG. 2

FIG. 3

FIG. 4

FIG. 5

FIG. 1 is a perspective view of a chuck wagon camper embodying my new design;

FIG. 2 is a perspective view thereof from the opposite side of that shown in FIG. 1;

FIG. 3 is a perspective view thereof from the opposite end of that shown in FIGS. 1 and 2;

FIG. 4 is a rear elevational view thereof, to a smaller scale; and

FIG. 5 is a front elevational view thereof to a smaller scale.

I claim:

The ornamental design for a chuck wagon camper, substantially as shown and described.
